CLAIM

The ornamental design for a wallboard removal tool head, as shown and described.

DESCRIPTION

FIG. 1 is a front isometric view of a wallboard removal tool head showing my new design;

FIG. 2 is a rear isometric view thereof;

FIG. 3 is a top plan view thereof;

FIG. 4 is a bottom plan view thereof;

FIG. 5 is a rear elevational view thereof;

FIG. 6 is a front elevational view thereof; and,

FIG. 7 is a left side elevational view thereof, the right side being a mirror image.

The broken line showing of the handle is for illustrative purposes only and forms no part of the claimed design.
